DESIGN FOR AN ASH RECEIVER

Kenneth C. Shyvers and Peter Jaskowiak, Chicago, Ill.

Application March 7, 1936, Serial No. 61,526

Term of patent 7 years

To all whom it may concern:

Be it known that we, Kenneth C. Shyvers and Peter Jaskowiak, both citizens of the United States and residents of Chicago, in the county of Cook and State of Illinois, have invented a new, original, and ornamental Design for an Ash Receiver, of which the following is a specification, reference being had to the accompanying drawing, forming a part thereof.

Fig. 2 is a top plan view of the same part being shown broken for convenience.

We claim:

The ornamental design for an ash receiver, substantially as shown and described.

Signed at Chicago, in the county of Cook and State of Illinois, this 28th day of February, 1936.

KENNETH C. SHYVERS.
PETER JASKOWIAK.
